UNITED STATES PATENT OFFICE.

HERBERT K. GREENMAN, OF CHICAGO, ILLINOIS.

DESIGN FOR A CASE FOR HOTEL-REGISTERS.

SPECIFICATION forming part of Design No. 36,299, dated April 28, 1903.

Application filed February 16, 1903. Serial No. 143,720. Term of patent 7 years.

To all whom it may concern:

Be it known that I, HERBERT K. GREENMAN, a citizen of the United States, residing at Chicago, in the county of Cook and State of Illinois, have invented and produced a new, original, and ornamental Design for Cases for Hotel-Registers, of which the following is a specification, reference being had to the accompanying drawings, forming part thereof.

10 In the accompanying drawings, Figure 1 is a face representation of my new design. Fig. 2 is an edge elevation.

My original design comprises the main center section 1, side sections 2 and 3, and top section 4. The top section has its ends 5 in reverse curve or ogee form, and its center portion has square openings 6 and 7, round openings 8, 9, and 10, and rectangular openings

11 and 12, with bars 13 extending across them. The surface of the top portion has the scroll-work located around the openings, and the outer edge of the top and side sections 2 and 3 is formed with the bead ornamentation 14.

Having described my invention, what I claim as new, and desire to secure by Letters Patent, is—

The ornamental design for a case for hotel-registers as herein shown and described.

In testimony whereof I have signed my name to this specification in the presence of two subscribing witnesses.

HERBERT K. GREENMAN.
